UNITED STATES PATENT OFFICE.

CLARENCE ZANE DAVIS, OF BUFFALO, NEW YORK, ASSIGNOR TO CYPHERS INCUBATOR COMPANY, OF BUFFALO, NEW YORK, A CORPORATION OF NEW YORK.

MOISTURE-SUPPLYING DEVICE FOR INCUBATOR-HEATERS.

No. 851,847.

Specification of Letters Patent.

Patented April 23, 1907.

Application filed August 31, 1905. Serial No. 276,540.

To all whom it may concern:

Be it known that I, CLARENCE ZANE DAVIS, a citizen of the United States, and a resident of Buffalo, in the county of Erie and State of New York, have invented certain new and useful Improvements in Moisture-Supplying Devices for Incubator-Heaters, of which the following is a specification.

This invention relates to devices for supplying moisture to the air by which incubators and like devices are heated or ventilated, and consists in the apparatus herein-after described and claimed.

In the drawings:—Figure 1 is a vertical section of an incubator heater supplied with this invention and of the adjacent portion of an incubator; Fig. 2 is an enlarged vertical section through the moisture device and through the plate of the heater to which it is attached; Fig. 3 is a cross-section on the line 3—3 of Fig. 2; and Fig. 4 is a perspective view of the moisture device.

In the drawing the incubator casing 1 is supplied with the heater, which in this instance has a hot air inlet 2 and a hot air exhaust 3. The inlet and the exhaust connect directly with a vertical pipe or tube 4, and has a top 5 provided with a central opening 6 that is adapted to be opened and closed by a damper 7 carried by the usual thermostat rod 8. Inside the pipe 4 is an inner tube 9 closed at the top, and having a lateral tube 10 connecting openings into the inner tube 9 and through the outer tube 4. Outside of the tube 4 is another tube 11, which does not extend as far downward as the other two tubes.

The inner or heating tube 9 is closed at the top, and preferably extends downwardly further than the lower end of the hot air tube 4. A shelf 12, preferably hinged to the incubator casing, and held up in place by a spring 13, supports a lamp 14 so that all the heat from said lamp passes into the tube 9 through the lateral tube 10 into the space between the tubes 4 and 9, and thence out to the air. The heat radiated from the tube 9 raises the temperature of the air in the space between the tubes 4 and 9, which thereupon, if the damper 7 is down or obstructs the free passage of the air out through the opening 6, will pass through the inlet 2 into the interior of the incubator, and after circulating

through the same will escape from the incubator by the pipe 3 and will rise through 55 the tube 4 and out through the opening 6 whenever the damper is sufficiently raised to permit this movement.

It is desirable to supply moisture with the air entering an incubator, particularly for 60 the purpose of hatching ducks, and for this purpose the present invention was produced. A box or tank is provided adapted to hold and to supply water continuously to an absorbent material, and the absorbent material 65 is placed in the space between the tubes 4 and 9 so as to be heated and cause evaporation of the water in said absorbent. Thus the evaporated water is fed to the heated air in the hot air space of the heater, and the 70 movement of such air carries the moisture on through the inlet 2 into the interior of the incubator.

In the present form of the moisture device, the tank 15 has its front and back formed 75 on concentric circles, and the connecting sides formed on radii of said circles. The front plate 16 extends to the bottom 17 of the tank, and has in it near said bottom an opening 18. The bottom 17 of the tank is 80 continued outward in a trough 19 so that water passing through the opening 18 will be held in the trough 19 and the water will be retained in the tank 15 until the water has evaporated or passed out of the trough 85 19 so far that a quantity of air may pass into the interior of the tank through the opening 18. This arrangement permits a constant feed of water through the opening 18, but slowly and automatically, and enables a 90 large quantity of water to be kept in the tank 15 for feeding outward therefrom. The front plate 16 is bent on substantially the same curve as that of the pipe 4.

Outside of the front plate 16 is a plate 20 95 constituting the absorbent support, and having one or more openings 21 (Fig. 2) at its bottom within the trough 19. Various absorbents may be used in connection with this device, but it is found that fibrous material, 100 such as asbestos cloth, strawboard, and blotting paper, or material having some stiffness even when moist, is most convenient in use. A sheet 22 of such a material is placed on the outer face of the absorbent supporting plate 105 20 and is held thereon by inwardly turned

vertical edges 23 of said plate, which inwardly turned edges overlap the edges of the sheet of absorbent material 22. The plates 20 and 16 are by their curvature adapted to make sufficient frictional pressure upon the tube 4 to support the tank and its connected parts in proper position, although, if need be, the block 24, or other means of support, can be placed under the tank.

10. The operation of the device is as follows:— Having moved the lamp 14 and depressed the shelf 12, the moisture device is raised into place with a portion of the tube 4 between the plates 16 and 20, and thus the sheet of 15 absorbent material 22 is in the hot air space between the tubes 4 and 9 with its inner surface exposed directly to the radiation from the heating tube 9, and still leaving the space between the tubes 4 and 9 free for the passage 20 of air into said space, and thence into the incubator passing the absorbent material 22. Water from the tank 15 passes out through the openings 18 and 21 and comes in contact with the lower edge of the absorbent sheet 22. It is 25 sucked up into this sheet by capillary attraction, and is evaporated from said sheet by the heat of the heating tube 9, and passes on into the incubator. The speed of evaporation can be increased and diminished by 30 varying the size of the sheet 22. A very open material will take up and give off water much more rapidly than will a closer and thicker fabric. The absorbent material must always extend to the bottom of the trough 35 19, or so far into the trough as to be in contact with the water fed out from the tank 15. The adjustment of the amount of evapora-

tion according to the time of year, and the particular circumstances under which the incubator is operated, can be produced by 40 varying the thickness, porosity, and area of the absorbent material.

The form of the incubator and of the heater and of the support for the lamp are all illustrative, and are not intended to limit the application of the moisture device to apparatus of these constructions.

What I claim is:—

1. The combination of an incubator heater having walls enclosing a hot air space for 50 heating the air to be delivered to an incubator, a water tank having a feed opening from its lower part, a sheet of absorbent material for absorbing the water fed from said opening, and guides upon the side of said water 55 tank for holding the side edges of said sheet.

2. The combination of an incubator heater having walls enclosing a hot air space for heating the air to be delivered to an incubator, a part of the outer wall of which space is a vertical partition, a water tank adapted to fit against the outer side of said partition, and having a lateral opening near its bottom, a trough adjacent to said opening and extending under said partition, a vertical plate extending from said trough inside said partition, and a sheet of absorbent material having one end in said trough and supported by 60 said plate.

CLARENCE ZANE DAVIS.
